UNITED STATES PATENT OFFICE.

JOHN D. HENON, OF PHILADELPHIA, PENNSYLVANIA.

DYEING APPARATUS.

Application filed September 3, 1921. Serial No. 498,198.

To all whom it may concern:

Be it known that I, JOHN D. HENON, a citizen of the United States, residing at Philadelphia, in the county of Philadelphia and State of Pennsylvania, have invented new and useful Improvements in a Dyeing Apparatus, of which the following is a specification.

My invention relates to new and useful improvements in a dyeing apparatus, and has for its object to construct such a device that the time required to dye yarns in dyeing tubs or vats of the propeller type now in general use will be considerably shortened as the dyeing liquid will be directed toward the material being dyed rather than permit it to flow about the material in the lines of least resistance.

Another object of the invention is to utilize the dyeing tubs or vats now in use by applying my improved deflectors or baffles within the dyeing compartment thereby giving a better distribution to the dyeing liquid and giving a more even distribution 25 of the color to the yarn or other material being dyed.

A further object of the invention is to provide an upper and lower grating of unique construction which will assist in deflecting the dyeing liquid as well as checking the flow thereof thereby preventing the yarn from becoming entangled or packing against the different parts of the dyeing apparatus.

A still further object of the invention is to provide an improved construction of dye vat cover and yarn stick support the latter being detachably connected with the former so as to be transported with the cover during 40 the time the yarn is being placed in or removed from the dyeing apparatus.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a plan view of a dyeing apparatus embodying my improvement, the cover and dye stick support being removed.

Fig. 2, is a side elevation thereof with the near side wall removed and the deflectors or baffles as well as certain of the other elements being shown in section to clearly illustrate the construction. 60

Fig. 3, is an end view thereof with the end wall and partition removed and the baffles or deflectors illustrated in section.

Fig. 4, is an end view of the vat cover 65 removed therefrom.

Fig. 5, is a similar view of the yarn stick support disconnected from the cover.

In carrying out my invention as here embodied, 2 represents the ordinary well known 70 dye vat or tub of any suitable size and shape and constructed from any desirable material they being generally formed of wood. The interior of the tub or vat is divided into two compartments 3 and 4 by a transverse vertical partition 5 the compartment 3 being the dyeing compartment while the one numbered 4 is the circulating compartment and these compartments are in communication with each other by means of a passageway 75 80 6 below the partition 5 and a passageway 7 above said partition. In the circulating compartment 4 is located suitable propelling or circulating means 8, here shown as a propeller which is mounted in any suitable 85 manner and driven by any desirable means.

Across the lower part of the compartment 3 and a short distance above the bottom of the dye vat or the tub are arranged or located a plurality of series of transverse 90 horizontal rods 9 forming a grating through which the dyeing liquid passes and said grating acts as a check to the flow of the dyeing liquid as well as deflecting the same so as to cause it to have a number of cross 95 currents thereby compelling it to flow into and through the yarn in the dyeing compartment rather than permit it to flow upward between the skeins of yarn or along the lines of least resistance. 100

Intermediate the height of the dyeing compartment 3 and around all the boundary walls thereof, as for instance the side walls and one end wall of the vat and the partition 5, is arranged or located a deflector or 105 baffle 10 in the form of a protuberance or rib projecting from the aforementioned walls and this baffle or deflector is semi-oval in cross section as plainly shown in Figs. 2 and 3. This baffle or deflector may be constructed of any suitable material in any desirable or well known manner but is pref- 110

erably formed from a number of wooden strips, boards or planks properly shaped and suitably attached to the different walls of the vat.

5 On top of the dye vat or tub is mounted a suitable cover 11 to which are fastened the cross beams 12 for strengthening the same and having eye bolts 13 connected therewith whereby a suitable hoisting apparatus may be attached for lifting the cover when the same is being placed on or removed from the dye vat. Depending from two opposite side edges of the cover are the side flanges 14 having longitudinal horizontal slots 15 therethrough for the passage of the dyeing liquid as will be hereinafter described and below these slots are mounted a plurality or series of rods 16 thereby producing the upper grating which is used for 10 the same purpose as the lower grating 9 and has the same action on the liquid as said grating 9. As the rods 16 forming the upper grating are mounted or set in the side flanges 14 said grating is removed from 15 the dye vat each time the cover is displaced and in practice said flanges 14 are each formed by two spaced members with suitable spacing blocks 17 and arranged between their adjacent edges, the spacing of said elements forming the aforementioned slots.

30 The numeral 18 denotes the yarn stick support and consists of members 19 in the same spaced relation to each other as are the depending flanges 14 of the dye vat cover, the said dye stick support adapted to be detachably connected with the said flanges whereby said support may be transported from place to place with the cover and hung within the vat when the cover is in place 35 thereon and although it will be obvious that any suitable means may be utilized for detachably connecting the support to said flanges I have shown a conventional means which consists of a number of hooks 20 on the flanges 14, said hooks cooperating with complementary means such as studs 21 or the strips or members 19 forming the support. The members of the yarn stick support are held in their spaced relation by suitable 40 means such as cross pieces 22 fixed to the ends of said strips or members. In the upper edge of each of the strips or members 19 are formed a plurality of notches 23 to receive the ends of the yarn sticks 24 from 45 which the skeins of yarn are hung in the ordinary manner and the open ends of said notches are closed by the coaction of the flanges 14 with the members 19 thus preventing the accidental displacement of the 50 yarn sticks.

55 In practice the dyeing liquid within the dye vat or tub should be caused to circulate very slowly first in one direction and then in the other and when circulating in the 60 direction which carries it from the compartment

ment 4 to the compartment 3 underneath of the partition 5 said liquid will pass through the grating formed by the bars 9 at the lower portion of the compartment 3 and be broken up into a number of cross currents flowing 70 upwardly through the compartment 3 and that portion of the liquid which would naturally follow the enclosing walls of the compartment 3, because of these points there is practically no resistance to the flow of 75 liquid but as these streams of liquid reach the baffle or deflector 10 it will be deflected inward and caused to flow through the yarn thus more evenly distributing the color and producing a better and more uniform dyeing 80 as well as facilitating and expediting the dyeing operation and as the liquid passes on up through the material being dyed it will finally flow through the slots 15 and then around the flanges 14 as well as over 85 the upper end of the partition 5 into the circulating chamber 4. When the flow of the liquid is reversed it will flow over the partition into the chamber 3 and also between the flanges 14 and the side walls of 90 the vat and then through the slots 15 into said chamber 3 where it will be checked and reflected by the upper grating and that portion flowing downward within the chamber 3 adjacent the enclosing walls and will be 95 again deflected by the baffle or deflector 10 finally passing beneath the partition 5 to the chamber 4.

100 This deflecting of the dyeing liquid as it passes through the compartment 3 makes it unnecessary to circulate the liquid at a high speed thereby eliminating or reducing to a minimum the possibility of the yarns being tangled or caused to double up or pack on the gratings.

105 As the yarn stick support is detachable from the cover of the dyeing apparatus said support may be set upon suitable holders to permit the yarns to dry, but while the yarn is being removed or placed upon the sticks 110 thereby saving considerable time in the operation of the dyeing apparatus for during the time one batch of yarn is being placed upon or removed from the sticks another batch may be submerged in the dyeing 115 liquid by the use of additional yarn sticks and a supporter therefor.

120 Of course I do not wish to be limited to the exact details of construction as herein shown as these may be varied within the limits of the appended claims without departing from the spirit of my invention.

125 Having thus fully described my invention, what I claim as new and useful is:—

1. A dyeing apparatus comprising a vat, a partition in said vat for dividing the same into two compartments, means in one of said compartments for circulating the dyeing liquid within the vat, and a deflector within the other compartment and located interme- 130

diate the height thereof to deflect the circulating liquid inwardly away from the walls of the vat and the aforementioned partition.

- 5 2. A dyeing apparatus comprising a vat, a partition in said vat for dividing the same into two compartments, means in one of said compartments for circulating the dyeing liquid within the vat, and a deflector or
10 baffle semi-oval in cross section fixed to the inner faces of the walls of the vat and the aforementioned partition for deflecting the dyeing liquid out of the lines of least resistance.
15 3. In a device of the character stated, a vat divided into two compartments communicating with each other at their upper and lower portions, a plurality of horizontal transverse bars at the lower portion of one
20 of the compartments to form a grating for

deflecting and checking the stream of dyeing liquid passing upwardly into the last mentioned compartment, means within said last mentioned compartment for deflecting a stream of liquid inwardly away from the 25 walls of the last mentioned compartment, a cover for the vat, slotted side flanges depending therefrom within the vat, a plurality of horizontal transverse rods fixed in said flanges to form a grating below the slots 30 in said flanges, the yarn stick support consisting of two spaced parallel members each having a plurality of notches in its upper edge to receive the ends of yarn sticks, and means for detachably connecting said support to the aforementioned flanges the latter acting as closures for said notches.

In testimony whereof, I have hereunto affixed my signature.

JOHN D. HENON.
